UNITED STATES PATENT OFFICE.

WILLIAM C. CARTER, OF ST. LOUIS, MISSOURI.

CARBURETER.

961,481.

Specification of Letters Patent. Patented June 14, 1910.

Application filed August 31, 1908. Serial No. 451,017.

To all whom it may concern:

Be it known that I, WILLIAM C. CARTER, a citizen of the United States, residing at St. Louis, Missouri, have invented a certain new and useful Improvement in Carbureters, of which the following is a full, clear, and exact description, such as will enable others skilled in the art to which it appertains to make and use the same, reference being had to the accompanying drawings, forming part of this specification, in which—

This invention relates to carbureters, and particularly to that type which is used on internal combustion engines.

One object of my invention is to provide a carbureter which is so constructed that the liquid fuel will be automatically separated or divided into minute particles before it is mixed with the air, thus enabling a low grade of fuel to be used.

Another object is to provide a carbureter which is so constructed that very little suction is required to draw the charge into the cylinders of the engine, thereby producing more power and a higher rate of speed than the carbureters heretofore in use.

Another object is to provide a carbureter that does not have to be adjusted or set for high speeds and low speeds, the carbureter being so constructed that the supply of fuel varies automatically as the speed of the engine varies.

Another object is to provide a carbureter having novel means for regulating the auxiliary air valve of the mixing chamber, said means being adapted to be controlled by an operator located some distance from the carbureter as, for example, by a person sitting in the driving seat of the automobile on which the carbureter is used. And still another object of my invention is to provide a carbureter having a mixing chamber which is so constructed that the air which enters same will be thoroughly mixed with vaporized fuel and thus produce a charge of the proper richness for each cylinder of the engine.

Other objects and desirable features of my invention will be hereinafter pointed out.

Figure 1 is a front elevational view of a carbureter constructed in accordance with my invention; Fig. 2 is a side elevational view of said carbureter, the mixing chamber being shown in vertical section; Fig. 3 is a vertical sectional view of the mixing chamber.

member, float chamber, jet tube and the members inside of which said jet tube is arranged; Fig. 4 is a perspective view of the auxiliary air valve for the mixing chamber; Fig. 5 is a vertical sectional view of the mixing chamber, said view being taken approximately on the line 5—5 of Fig. 2; and Fig. 6 is an enlarged horizontal sectional view taken approximately on the line 6—6 of Fig. 3.

Referring to the drawings which illustrate the preferred form of my invention, 1 designates an approximately cup-shaped hollow member that forms a float chamber, and 2 designates a tubular-shaped portion 70 on one side of said member that forms what I will term a starting reservoir. This tubular-shaped portion 2 is preferably formed integral with the member 1, and a duct 3 leads from the lower end of said tubular-shaped portion to the interior of the cup-shaped member 1 so as to permit the liquid fuel in the float chamber to flow into the starting reservoir or, rather, into the jet tube that communicates with said duct, as 75 hereinafter more clearly described. A removable top 8 is detachably connected to the cup-shaped member 1 by means of fastening devices 8^a, and, if desired, the bottom of said member 1 can be provided with a 80 removable plug or stopper 1^a, as shown in Fig. 3, so as to enable the float chamber to be drained out when sediment collects therein.

A float 4, which preferably consists of a 90 hollow metal ball, is located inside of the float chamber for automatically actuating a lever 4^b which controls a valve 4^c that admits the liquid fuel into the float chamber, said float 4 operating to always keep the 95 fuel in the float chamber at a certain level. I have herein shown a ball valve 4^c for controlling the supply of liquid fuel to the float chamber but I wish it to be understood that it is immaterial so far as my broad 100 idea is concerned, what type of valve is used for this purpose. The liquid fuel is conducted into the float chamber by means of a pipe 5 leading from a fuel tank, not shown, and communicating with a hollow 105 portion 5^a formed in the top 8 of the float chamber, the fuel flowing from the hollow portion 5^a into the float chamber through an opening which the ball valve 4^c closes, as shown in Fig. 3.

2 A mixing chamber 6 provided with a flange or other suitable device for connecting it to the intake pipe A leading to the cylinders of the engine on which the carburetor is used, is located above the float chamber, and in the construction herein shown said mixing chamber consists of a cored-out casting that is connected to the top 8 of the cup-shaped member 1 either by 5 suitable fastening devices or by casting it integral with said top 8. The top 8 is provided with an integral sleeve 17 that forms a continuation of the tubular-shaped portion 2 on the member 1, and a duct or conduit 7 that is formed in said top 8, as shown in Fig. 3, establishes communication between the mixing chamber and the starting reservoir so as to permit the contents of said starting reservoir to be drawn up into the 10 mixing chamber when a suction is created in the cylinders of the engine.

25 A vertically disposed tube 9 which I term a "jet tube" communicates with the duct 3 which leads from the float chamber into the lower end of the starting reservoir so that the liquid fuel can flow from the float chamber into said tube and thence escape laterally therefrom through small perforations or holes 10 formed in said tube and located 30 in different levels or in different horizontal planes. The upper end of the jet tube is closed by a nut 15, hereinafter described, so that when the air is drawn out of said tube a partial vacuum will be created therein 35 which causes the liquid fuel to rise in said tube. An air pipe 11, which surrounds the jet tube 9 and projects into the starting reservoir, forms a conduit or passageway through which air is drawn into the mixing 40 chamber by the suction in the cylinders of the engine, the upper end of said air pipe being open or constructed in such a manner that air can rush downwardly through same so as to create a partial vacuum in the jet 45 tube and also vaporize the liquid fuel that emerges from the jet tube. The lower end of this air pipe 11 terminates above the bottom of the starting reservoir, as shown in Fig. 3, so as to permit the vaporized fuel to 50 pass upwardly around said pipe to the duct 7 and then into the mixing chamber 6. The air rushing down through this air pipe 11 creates a partial vacuum in the jet tube which causes the liquid fuel to rise automatically in said tube and escape through the 55 perforations 10 therein in the form of a spray or a number of fine jets of liquid fuel that are vaporized or converted into gas as soon as they become mixed with the air 60 which is sucked into the mixing chamber. As the suction in the cylinders of the engine increases the vacuum in the jet tube will, of course, increase proportionately and thus cause the fuel to rise higher in the jet tube 65 and bring more of the ports 10 into service;

70 or, in other words, more jets of fuel will emerge from the jet tube as the suction in the mixing chamber increases. Consequently, the supply of fuel which is drawn into the mixing chamber will vary automatically as the speed of the engine varies for the suction from the cylinders controls the height of the liquid fuel in the jet tube.

75 By separating or splitting the liquid fuel in the manner above described I am able to use a low grade of fuel for the fuel is divided into such minute particles that it vaporizes quickly when it comes in contact with the air that rushes down through the air pipe 11. More power and a higher rate 80 of speed is also obtained from the engine when the liquid fuel is separated into minute particles before it is vaporized for only a low suction is required to draw the charge into the cylinders of the engine, 85 That is to say, with a carburetor of this construction only a few ounces of suction is required to draw a charge into the cylinders so that the engine will operate at a higher speed and generate more power than if several pounds of suction were required to draw in the charge. It will be noted that the air which vaporizes the liquid fuel enters the upper end of the air pipe 11 and then passes out of the lower end of said pipe 90 after it has vaporized the jets of fuel that emerge from the jet tube.

95 The object of having the air travel in an opposite direction to that in which the liquid fuel travels as it rises in the jet tube 10 is to prevent the supply of fuel that leaves the jet tube from becoming so great that too rich a mixture will be produced. For example, if the air entered the lower end of the air pipe 11 and then passed upwardly 10 through said pipe and out the upper end thereof to the mixing chamber the jets of fuel that emerge from the lower ports in the jet tube would be converted into a gas which would tend to obstruct or close the 11 air pipe from the supply of fresh air. Consequently, the quantity of liquid fuel that emerged from the jet tube would be so much greater than the quantity of air that passed up through the air pipe that the supply of 11 air would not be sufficient to produce a proper mixture. In my improved construction this cannot occur for the supply of fresh air is always above the level of the fuel in the jet tube so that it will be impossible for the air pipe to become choked or 12 filled with pure gas. The result is that the proper amount of air will always be supplied and thus produce a charge of a proper richness.

12 The perforations 10 in the jet tube are preferably arranged spirally or out of vertical alignment with each other so that each jet of fuel will become mixed with a different particle of air, the jets of fuel emerging 13

from the jet tube in different horizontal planes and also different vertical planes so that the jet which emerges from one perforation will not mix with the air that has become mixed with the jet directly above it.

As shown in Fig. 3, the perforations or holes 10 in the jet tube are so small and are so close together that the supply of fuel increases gradually so that no perceptible change is noticed in the explosions as the speed of the engine increases.

The lowest perforation 10 in the jet tube is below the normal level of the fuel in the float chamber so that when the engine stops some of the fuel in the lower end of the jet tube will flow through the lowest perforation therein into the starting reservoir. The quantity of liquid fuel that collects in the bottom of the starting reservoir is just sufficient to produce a starting charge for the cylinder of the engine, and when the engine is cranked a suction will be created in the mixing chamber which causes the fresh air to rush down through the air pipe 11 and vaporize the fuel in the bottom of the starting reservoir, said vaporized fuel being then drawn up around the outside of the air pipe and through the duct 7 into the mixing chamber from which it passes into the cylinders of the engine. As the engine continues in operation a steady current of air will be drawn down through the air pipe and thus vaporizes the jets of fuel that emerge from the jet tube, the air that is drawn down through said air pipe being sufficient to produce a charge of the proper richness up to a certain speed of the engine. When the engine exceeds this speed and a greater suction is thus created in the mixing chamber the liquid fuel that escapes from the jet tube will exceed the quantity of air that passes down through the air pipe, and consequently, the charge that is drawn into the mixing chamber will be too rich to form an explosive gas. To compensate for this, or to cut down this very rich charge of vaporized fuel, I have provided the mixing chamber with an auxiliary air valve, hereinafter described, that opens automatically when a certain suction is obtained so as to admit a sufficient quantity of fresh air to produce a charge of the proper richness.

I prefer to arrange the air pipe 11 inside of a hot water chamber so as to heat said pipe and also the jet tube and thus raise the specific gravity of the fuel and cause it to vaporize quickly. In the construction herein shown, said hot water chamber is formed by a comparatively large tube 14 that surrounds the air pipe 11, the upper end of said tube 14 being closed by a plug or member 12 provided with a number of radially disposed holes or openings 13 that form air ports which permit air to enter the upper end of the air pipe 11, said pipe

being connected to the member 12 below the radially disposed holes therein. The closure for the upper end of the jet tube 9 consists of a plug or nut 15 screwed into the member 12, as shown in Fig. 3, and provided with a tapered recess or socket that receives the beveled upper end of the jet tube. The lower end of said jet tube is also beveled so that it will fit snugly in a tapered socket in the bottom of the starting reservoir 2. By screwing the plug 15 downwardly the jet tube will be forced snugly into its tapered seats or recesses and thus securely clamped in position. This forms a very efficient and simple means for retaining the jet tube in position and it enables said tube to be removed easily and it also eliminates the possibility of breakage such as would be apt to occur if the jet tube had a screw-threaded connection with members that support it and maintain it in position. It is immaterial, however, so far as my broad idea is concerned, how the jet tube is retained in position so that I do not wish it to be understood that my invention is limited to this exact construction.

The large tube 14 that forms the water chamber, is connected to the sleeve 17 on the top 8 of the cup-shaped member 1 by means of a nut 16 through which the air pipe passes, said nut filling the space between the exterior of the air pipe and the interior of the tube 14 so as to close the lower end of said tube. The water that is supplied to said tube 14 is preferably obtained from the water jackets on the cylinders of the engine on which the carburetor is used, the upper end of the tube 14 communicating with a pipe 18 and the lower end of said tube communicating with a pipe 19 so that the water in the cylinder jackets can circulate through the tube 14. Said pipes 18 and 19 are connected to nipples that are screwed into bands 18^a and 19^a which surround the tube 14, or, if desired, said nipples can be tapped directly into the tube 14 if the material from which said tube is formed is thick enough to be provided with screw-threaded openings.

While I have herein stated that the hot water chamber consists of a tube 14 that is detachably connected to the top 8 of the cup-shaped member 1, it will, of course, be obvious that the member 14 can be cast integral with said top 8 and also provided at its upper end with an integral portion 12 for receiving the clamping nut 15. Means of the character above described for heating the air before it is drawn into the mixing chamber is a very desirable feature but I do not wish it to be understood that it is an essential feature of my carburetor for the carburetor will operate satisfactorily without this hot water chamber.

A throttle valve 20 is arranged in the out-

let opening 20^a of the mixing chamber, and the stem of said valve is provided with an arm 20^b, as shown in Fig. 2, to which a link 20^c is connected for actuating said valve. A flange 21, which is preferably formed integral with the casting that constitutes the mixing chamber, surrounds the outlet opening 20^a and depends downwardly therefrom, as shown in Figs. 3 and 5, so as to prevent the air that is drawn into the mixing chamber from rushing through the outlet opening before said air has become thoroughly mixed with the vaporized fuel that enters the mixing chamber through the conduit 7. By constructing the mixing chamber in this manner; namely, by providing it with a depending flange that surrounds the outlet opening, the air will be drawn uniformly from all points of the mixing chamber and thus produce a charge of the proper richness for each cylinder of the engine, said flange 21 acting as a baffle to prevent the air from passing through the outlet opening of the mixing chamber before it has become thoroughly mixed with the vaporized fuel.

As previously stated, the mixing chamber is provided with an auxiliary air valve which opens automatically when the engine attains a certain speed. This auxiliary air valve is designated by the reference character 22 and is shown clearly in Figs. 1, 2 and 4 of the drawings. Said valve 22 is carried by an arm 23 pivotally mounted on a stud shaft 23^a that is carried by a stationary arm 24 which is preferably formed integral with the face plate 25 of the mixing chamber. The air valve 22 is seated or held in its closed position by means of a spring 32 connected at one end to the arm 23 which carries said valve, and having its opposite end connected to an adjustable arm 31 which is controlled by the operator who is stationed some distance from the carburetor, as, for example, the person who is driving the automobile on which the carburetor is used. This arm 31 is connected to a rock shaft 29 journaled in a bearing 30 on the face plate 25 of the mixing chamber, and said rock shaft is provided with an arm 37 to which a link 38 is connected, as shown in Fig. 2, so that the operator can move the shaft 29 and thus vary the tension which the spring 32 exerts on the opening movement of the auxiliary air valve 22. Instead of having the spring 32 connected directly to the arm 31 I prefer to provide an adjustable connection between said spring and arm. In the construction herein shown said adjustable connection consists of a shaft 33 journaled in the upper end of the arm 31 and provided with an arm 34 that cooperates with a rack bar 35 on the arm 31, a coiled expansion spring 36 being interposed between a shoulder on the shaft 33 and the

bearing on the arm 31 on which said shaft is mounted so as to hold the handle 34 in mesh with the rack bar 35. The upper end of the spring 32 is eccentrically connected to the shaft 33, or in other words, the upper end of the spring 32 is connected at one side of the longitudinal center of said shaft so that when said shaft is turned the length of said spring will be varied, thereby causing the tension of said spring to be varied. When the carburetor is installed the shaft 33 is adjusted so that the tension of the spring 32 will just hold the auxiliary air valve 22 seated. Thereafter, the adjustment of the spring 32 is controlled by the link 38 connected to the arm 37 of the rock shaft 29. To prevent the air valve from opening too quickly I have provided said valve with a piston 27, as shown in Fig. 2, that operates in a dash-pot 26 at one side of the mixing chamber 6, said piston 27 being pivotally connected to the air valve by means of a link 28. The auxiliary air valve 22 is so adjusted that it will open automatically when the vaporized fuel that emerges from the jet tube extends a certain amount, as previously stated, and when the quantity of fuel that emerges from said jet tube increases the air valve 22 will open farther and thus admit proportionately the same amount of air to the mixing chamber, said valve closing automatically when the fuel in the jet tube falls or seeks a lower level. If the operator finds that the air admitted to the mixing chamber is not sufficient to produce a charge of the proper richness, or if he finds that too much air is being admitted to the mixing chamber, he moves the link 38 so as to change the position of the rock arm 31 and thus vary the tension which the spring 32 exerts on the opening movement of the air valve.

When the air valve is closed the rock arm 31 normally occupies such a position that the spring 32 is arranged at an angle of approximately 45° relatively to the straight portion of the arm 23 that carries the air valve. When said rock arm 31 is moved to the left, looking at Fig. 4, the spring 32 will be arranged more nearly parallel to the straight portion of the valve-carrying arm 115 and consequently said spring will not exert as much tension on the valve when it opens, thereby permitting the valve to open farther and thus admit more air to the mixing chamber than when the rock arm is arranged in its normal position. When the rock arm 31 is moved to the right, looking at Fig. 4, the spring 32 will be arranged at a greater angle relatively to the straight portion of the valve-carrying arm or more nearly at right angles to said straight portion so that greater tension will be exerted on the valve when it opens.

To state it in another way, the spring 32 exerts a certain tension on the opening

movement of the air valve when the rock arm is in its normal position, as shown in Fig. 4, so that a certain suction in the mixing chamber will cause the air valve to open a certain distance. If the operator finds that the air valve does not open far enough, when the arm 31 is in this position, to admit sufficient air to produce a charge of the proper richness, he moves the arm 31 to the left so as to reduce the tension which the spring 32 exerts on the opening movement of the air valve. This, of course, will permit the valve to open farther before the normal tension on the same is again established, and, consequently, a greater quantity of air can enter the mixing chamber. If the operator finds that too much air is being admitted to the mixing chamber he moves the arm 31 to the right so as to increase the tension which the spring 32 exerts on the valve and thus prevent said valve from opening as far as it did when the spring was arranged more nearly parallel to the straight portion of the valve-carrying arm.

From the foregoing it will be seen that the operator can accurately govern the quantity of air that is admitted to the mixing chamber when the motor is running for the movement of the rock arm 31 varies the tension which the spring exerts on the air valve.

While I have specifically described one form of mechanism for controlling and adjusting the auxiliary air valve it will, of course, be obvious that various other means could be employed for this purpose and therefore I do not wish it to be understood that my invention is limited to the construction herein shown for adjusting the air valve.

Having described the details of construction of my improved carburetor, I will now describe the operation of same.

When the engine stops some of the fuel in the float chamber will flow through the lowermost port of the jet tube into the starting reservoir 2 and thus be in position to be drawn into the mixing chamber when the engine is cranked. The suction produced in the mixing chamber by cranking the engine causes a current of air to pass downwardly through the air pipe 11 and thus vaporize the liquid fuel from the bottom of the starting reservoir and carry it into the mixing chamber. As the engine continues in operation a steady current of air will be drawn down through the air pipe 11, thus creating a partial vacuum in the jet tube which causes the fuel to rise in said tube and pass through the perforations 10 therein, the level of the fuel in said jet tube varying as the suction in the mixing chamber varies. The jets of fuel that emerge from the jet tube are vaporized and carried into the mixing chamber by the current of air that passes downwardly through the air pipe, and as said air pipe

and jet tube are heated by the water that circulates through the tubular-shaped member 14 in which the air pipe is arranged, the liquid fuel in the jet tube and also the air that passes through said pipe will be heated and thus cause the fuel to vaporize quickly.

The air that is drawn down through the air pipe 11 is sufficient to produce a charge of the proper richness up to a certain speed of the engine but when the engine exceeds this speed the fuel that escapes from the jet tube will be so much greater than the quantity of air that passes through the air pipe that the mixture will be too rich to form explosive gas. The air that is admitted to the mixing chamber through the auxiliary valve 22, however, cuts down this very rich charge and thus produces a charge of the proper richness. The auxiliary air valve 22 is so adjusted that it opens automatically when the vaporized fuel that emerges from the jet tube exceeds a certain amount, and as the quantity of fuel that escapes from said tube increases the valve 22 opens farther and thus admits proportionately the same amount of air to the mixing chamber.

It is well-known that in cold weather air is lighter and quicker in its action than in warm weather when the air is heavy and sluggish. Consequently, a greater quantity of air will flow through an opening of a certain size in cold weather than in hot weather. With my improved carburetor it is a very simple matter to adjust the air valve when the weather varies for all that the operator has to do is to move the link 38 until the tension on the air valve is just right to permit said valve to admit the proper amount of air to the mixing chamber.

Having thus described my invention, what I claim as new and desire to secure by Letters Patent is:

1. A carburetor provided with a jet tube having its upper end closed and its lower end communicating with a supply of liquid fuel, said tube being provided intermediate its ends with a number of open eduction ports located at different levels, and means for causing a current of air to pass downwardly adjacent said tube so as to create a partial vacuum therein and thus cause the fuel to rise automatically in said tube and pass laterally through the ports therein, the quantity of fuel that emerges from said jet tube varying automatically.

2. A carburetor having a jet tube that is provided intermediate its ends with a plurality of eduction ports that are always open and which are located at different levels, means for supplying liquid fuel to the lower end of said jet tube, and means for causing air to pass downwardly around said tube and thus vaporize the fuel that rises in said tube and emerges from the ports therein when a suction is created in

the mixing chamber of the carburetor, the level of the fuel in said tube varying automatically as the suction in the mixing chamber varies.

5 3. A carburetor comprising a vertically disposed jet tube having its upper end closed, said tube being provided with a number of fine perforations or holes located in different horizontal levels or in different 0 horizontal planes, means for supplying liquid fuel to the lower end of said tube, a member which surrounds said jet tube to form an air passageway, the upper end of said member being open to the atmosphere, 5 and a mixing chamber communicating with the lower end of said member so that air will be drawn downwardly through said member when a suction is created in the mixing chamber, the air that is drawn down 20 through said member causing the fuel to rise automatically in the jet tube and escape through the ports therein and thus be vaporized by said air.

•4. A carburetor comprising a mixing 25 chamber, a float chamber adapted to contain liquid fuel, a jet tube communicating with said float chamber and having its upper end closed, said tube being provided with a plurality of eduction ports located at different 30 levels that permit the fuel in said tube to escape laterally in the form of a fine spray or plurality of jets, and a member surrounding said jet tube to form an air passageway, the lower end of said member 35 being in communication with the mixing chamber and the upper end of said member being so constructed that air can enter same and travel downwardly into the mixing chamber when a suction is created in said 40 mixing chamber, said downwardly rushing air causing a partial vacuum to be created in the jet tube and thus causing the liquid fuel to rise and fall in said tube as the suction in the mixing chamber varies.

45 5. A carburetor comprising a mixing chamber, a float chamber, a vertically disposed jet tube having its upper end closed and its lower end communicating with the float chamber so as to receive fuel therefrom, said tube being provided intermediate its ends with a number of fine perforations located at different levels, and an approximately tubular-shaped member surrounding said jet tube and having its upper end open 55 to the atmosphere, the lower end of said member communicating with the mixing chamber so that air will flow downwardly around the jet tube when a suction is created in the mixing chamber and thus create a 60 partial vacuum in the jet tube which causes the fuel to rise therein and escape through said perforations.

6. A carburetor comprising a mixing chamber, a vertically disposed tube having its

upper end closed, means for supplying liquid 65 fuel to the lower end of said tube, said tube being so constructed that the fuel therein can escape laterally at different levels intermediate the ends of the tube, means for causing air to pass downwardly around said tube 70 when a suction is created in the mixing chamber so as to vaporize the fuel that emerges from the tube and also create a partial vacuum in the upper portion of the tube which causes the level of the fuel in 75 said tube to vary, and separate means for supplying air to the mixing chamber.

7. A carburetor provided with a vertically disposed jet tube having a plurality of eduction ports located in different horizontal 80 planes and being always open, the upper end of said jet tube being closed, a mixing chamber, an air pipe located outside of the mixing chamber and surrounding said jet tube, the lower end of said air pipe communicating 85 with the mixing chamber so that air will be drawn down through said pipe when a suction is created in the mixing chamber and thus create a partial vacuum in the jet tube which causes the level of the fuel therein to vary, and an automatic valve for admitting air into the mixing chamber when the suction in said mixing chamber reaches a certain degree.

8. A carburetor provided with a member 95 that forms a float chamber, a valve for admitting liquid fuel into said float chamber, a float in said member for controlling said valve, a jet tube communicating with the float chamber for receiving the fuel therein 100 and being provided with a plurality of ports located at different levels so that the supply of fuel which emerges from the jet tube will vary as the level of the fuel in said tube changes, a mixing chamber, and means for 105 causing air to travel downwardly around the exterior of said tube to mix with the fuel that emerges from the jet tube and then pass into the mixing chamber when a suction is created in said mixing chamber. 110

9. A carburetor comprising a mixing chamber, a float chamber, a float for controlling the valve that admits fuel into said float chamber, a vertically disposed tube communicating with the float chamber and provided with a number of fine eduction ports located at different levels that permit the fuel therein to escape in the form of a fine spray, and an air pipe surrounding the jet tube and having its lower end communicating with the mixing chamber so that a current of air will pass downwardly through said pipe and vaporize the fuel that emerges from the jet tube when a suction is created in the mixing chamber, said current of air 120 creating a partial vacuum in the upper portion of the jet tube and thus causing the level of the fuel to vary. 125

10. A carbureter provided with a vertically disposed air pipe having its upper end communicating with the atmosphere, a mixing chamber communicating with the lower end of said pipe so as to draw air down through same when a suction is created in said mixing chamber, a jet tube arranged inside of said air pipe and provided intermediate its ends with a plurality of eduction ports located at different levels, and means for supplying liquid fuel to the lower end of said jet tube, the upper end of said tube being closed so that a partial vacuum will be created therein by the air rushing down the air pipe and thus causing the liquid fuel to rise in the jet tube and escape laterally through the eduction ports therein at different levels as the level of the fuel varies.
- 20 11. A carbureter provided with an approximately tubular-shaped member that forms a water chamber, means for conducting water into and out of said chamber, an air pipe extending through said member and having its lower end communicating with the mixing chamber of the carbureter and its upper end communicating with the atmosphere so that air will be drawn down through same when a suction is created in the mixing chamber, and a vertically disposed jet tube arranged inside of said air pipe and communicating with a supply of liquid fuel, said tube being provided with ports located at different levels so that the fuel which emerges therefrom will vary as the suction in the mixing chamber varies.
12. A carbureter provided with an approximately cup-shaped member that forms a float chamber, an approximately tubular-shaped portion on one side of said member that forms a starting reservoir, said portion having its lower end closed, a duct leading from the float chamber into said tubular-shaped portion, a vertically disposed jet tube communicating with said duct and provided with a plurality of ports that permit fuel to escape therefrom into said starting reservoir, some of said ports being lower than the normal level of the fuel in the float chamber, a removable top for said cup-shaped member, a mixing chamber carried by said top, an approximately tubular-shaped member carried by said top to form a water chamber, and an air pipe arranged inside of said tubular-shaped member and surrounding said jet tube, the upper end of said air pipe being exposed to the atmosphere and the lower end of said air pipe projecting into the starting reservoir and communicating with the mixing chamber.
13. A carbureter provided with a float chamber, a vertically disposed jet tube communicating with said float chamber and provided with a plurality of ports that permit

liquid fuel to escape therefrom, an air pipe surrounding said jet tube and having its upper end open to the atmosphere, a mixing chamber communicating with the lower end of said air pipe, an approximately tubular-shaped member surrounding the air pipe to form a water chamber, and a removable device carried by said tubular-shaped member for clamping the jet tube in position.

14. A carbureter comprising a mixing chamber, means for vaporizing the liquid fuel and conducting it into said mixing chamber, a hinged or swinging air valve for admitting air into the mixing chamber, a swinging spring for holding said valve seated, and means whereby said spring can be bodily shifted by a person stationed some distance from the carbureter so as to vary the tension which said spring exerts on the opening movement of the air valve.

15. A carbureter comprising a mixing chamber, means for vaporizing liquid fuel and conducting it into said mixing chamber, a swinging valve for admitting air into the mixing chamber, a spring for holding said valve seated, and means for bodily shifting said spring to vary the tension which it exerts on the opening movement of said air valve.

16. A carbureter provided with a mixing chamber, an air valve for admitting air into the mixing chamber, a swinging member that carries said air valve, a manually operable rock arm, and a coiled spring connected to said rock arm and to the member that carries the air valve in such a manner that movement of said rock arm bodily shifts said spring and thus varies the tension which it exerts on the opening movement of the air valve.

17. A carbureter comprising a mixing chamber, means for vaporizing fuel and introducing it into said mixing chamber, an air valve for admitting air into the mixing chamber, a swinging member carrying said air valve, a spring for holding said valve seated, and means for bodily shifting said spring to vary the tension which it exerts on the air valve.

18. A carbureter provided with a mixing chamber, a valve for admitting air into said chamber, a pivotally mounted arm carrying said valve, a coiled spring having its lower end pivotally connected to said arm, and means for swinging the upper end of said spring to bodily shift same and thus vary the tension which it exerts on the opening movement of the air valve.

19. A carbureter provided with a mixing chamber, means for mixing liquid fuel with air and conducting it into said mixing chamber, an auxiliary air valve for admitting air into the mixing chamber, a pivotally mounted arm carrying said valve, a manually op-

erable rock arm whose free end is adapted to move toward and away from the pivot of the valve-carrying arm, and a coiled spring connected to the free end of said rock arm and to the arm that carries the valve.

20. A carburetor comprising a mixing chamber, means for vaporizing liquid fuel and conducting it into said mixing chamber, an auxiliary air valve for admitting air into the mixing chamber, a hinged arm that carries said valve, a coiled spring for holding said valve seated, means for shortening

or lengthening said spring, and independent means for bodily shifting said spring to vary the tension which it exerts on the opening movement of the air valve. 15

In testimony whereof I hereunto affix my signature in the presence of two witnesses, this twenty-seventh day of August 1908.

WILLIAM C. CARTER.
